UNITED STATES PATENT OFFICE.

WILLIAM WALLACE WHITE, OF NEW YORK, N. Y., ANCILLARY EXECUTOR
OF JOHN VERITY, DECEASED.

SHIP'S ANCHOR.

SPECIFICATION forming part of Letters Patent No. 710,825, dated October 7, 1902.

Application filed February 24, 1902. Serial No. 95,262. (No model.)

To all whom it may concern:

Be it known that JOHN VERITY, who was a subject of the King of England, and a resident of 35 Rufford road, Fairfield, Liverpool, 5 in the county of Lancaster, England, but is now deceased, did invent a certain new and useful Improved Ship's Anchor, of which the following is a specification.

This invention has reference to ships' anchors of the type called "stockless" or "patent" anchors; and it has primarily for its object to provide a construction by which certain defects hereinafter described are obviated and also to increase its holding or anchoring effect.

Drawings illustrative of the invention are annexed hereto.

Figure 1 is an end elevation, and Fig. 2 a side elevation, of a stockless or patent anchor 20 fluke and head portion provided with the improvements.

According to this invention the extremities of the flukes of anchors of the kind herein referred to are provided on each side with 25 a rib or plane the external surface of which extends on either side of the fluke-tip at right angles to the general plane of the flukes. They are so arranged and provided that they constitute the part or surface of the fluke- 30 tips which will come in contact with the ship's side—that is, the plating—when the anchor is being weighed.

Referring to the drawings, *a* designates the head portion of the anchor. *c* represents the 35 flukes, and *b* represents the ribs or planes provided at the extremities or tips *c'* of the flukes *c*, on either side of same. The ribs or planes *b* are disposed at right angles to the general plane of the flukes and the tips *c'* 40 and are of cuneiform construction, having the maximum width at the tip of the fluke, and they are flush with the extreme end of the parts *c'*, and their outer edges lie at right angles to the plane of the parts *c'*.

When the anchor is being weighed in the ordinary manner and is in contact with the ship's side *x*, the surface formed by the outer

edges of the ribs *b* on the tips *c'* of the flukes is presented to and comes in contact with the vessel's plates at an inclination or angle, and 50 this surface being greater in extent or length than the thickness of the projecting plate edges *x'* of the ship's plating *x* and at an angle, as illustrated in relation thereto, the upward pull of the anchor *a* in the direction of 55 the arrows causes the anchor to be pressed outward away from the plating *x* when the leading edges or faces of the ribs *b* come against these edges, owing to the pressure of the incline against the external corner *x'* of 60 the projecting plate edge. By this means the tips *c'* of the anchor-flukes *c* cannot get under and be caught by these projecting edges *x'* of the plates when the anchor is hauled up.

The holding or anchoring effect of the anchor is increased and improved by providing the flukes *c* with a vertical projecting rib or flange *d* on either side extending at right angles to the general plane of the fluke down the center of said fluke from the head toward 70 the tip, where it diminishes off, as shown at *e* in the drawings. These vertical projecting ribs or flanges give the anchor at the center of the fluke a section somewhat in the form of a cross, as shown on the right-hand fluke 75 of Fig. 2.

What is claimed in respect of the herein-described invention is—

In a ship's anchor of the kind herein referred to, the flukes *c*, with heart-shaped 80 fluke-tips *c'*, disposed in the general plane of said flukes, and projecting cuneiform ribs *b* on either side of the tips *c'*, said ribs forming a flat surface at the end of the fluke-tips *c'* and extending at each side at right angles to 85 the plane of same, and tapering inward toward the surface of the tip, substantially as described.

WILLIAM WALLACE WHITE,
Ancillary executor of the estate of John
Verity, deceased.
